PROCESS OF PRODUCING CYCLOALKADIENE FROM PETROLEUM OILS

Charles E. Morrell, Westfield, Harold W. Scheeline, Llewellyn Park, and Carl S. Carlson and Harry J. Heineman, Jr., Elizabeth, N. J., assignors to Standard Oil Development Company, a corporation of Delaware

Application September 24, 1946, Serial No. 699,014

1 Claim. (Cl. 260—666)

1

This invention relates to a practical method and means for obtaining cycloalkadienes of high purity from cracked petroleum oils.

Prior to the present invention there has been no economically feasible method of procuring cycloalkadienes from petroleum oils.

It is known that limited amounts of cyclopentadiene have been commercially available only by processing of coal tar oil forerunnings, in which cyclopentadiene is present as the monomer. This cyclopentadiene is recovered from the light ends of the coal tar forerunnings, containing mainly benzene, by the steps of:

(1) Heating the light ends under high pressure without vapor separation until as much of the monomer as possible is polymerized therein,

(2) Distilling the aromatic light ends from the polymer which remains as a bottoms or residue,

(3) Vacuum distilling the cyclopentadiene polymer from the bottoms, and

(4) Cracking the thus purified cyclopentadiene polymer distillate in a column packed with iron turnings or similar material.

The method by which cyclopentadiene is recovered from light ends of coal tar forerunnings is not practically applicable to cracked petroleum distillates which contain very small amounts of cyclopentadiene monomer and in which many other hydrocarbons of unstable characteristics are present in much larger quantities. No satisfactory method has been found for separating cyclopentadiene polymer from cracked petroleum products such as may be obtained, for instance, from thermal cracking of gas oils or heavy naphthas.

An object of this invention is to provide a commercially feasible process of obtaining cycloalkadienes, such as, cyclopentadiene and methyl cyclopentadiene, each in a substantially pure state, from cracked petroleum products by collecting in the bottoms of an aromatic naphtha distillate, polymers of the cycloalkadienes formed in the cracking and naphtha fractionation operation, then heat treating and processing the aromatic distillate bottoms in such a manner as to evolve substantially pure monomer distillates therefrom.

Among its objects, this invention is primarily concerned with obtaining C₅ to C₈ cycloalkadienes from cracked petroleum distillates produced under sufficiently severe vapor phase cracking conditions as to form considerable amounts of mono-olefins, diolefins, and aromatics. The mono-olefins, or alkenes, include largely ethylene, propylene, and butylenes. The diolefins include the non-cyclic alkadienes and the cycloalkadienes such as, butadienes, pentadienes, cyclopentadiene, methyl and

2

dimethyl cyclopentadienes, hexadienes, cyclohexadienes, methyl cyclohexadiene, dimethyl cyclohexadienes, and the like. The aromatics include benzene and its homologs. The cracked products issuing from the cracking zone are quenched to a temperature at which thermal polymerization of the non-cyclic unsaturated hydrocarbons is repressed in order to obtain a high yield of the low boiling alkadienes, such as butadiene, pentadienes, and the like.

This invention is also concerned with effecting separation of an aromatic naphtha fraction from the higher boiling cracked products and separating from the lower boiling unsaturated hydrocarbons a heavy portion of the aromatic naphtha fraction as bottoms in such a manner as to accumulate cycloalkadiene polymers in this heavy aromatic naphtha fraction before it is subjected to a heat treatment under proper conditions for converting the cycloalkadiene polymers to monomers without undesired side reactions, and subsequently isolating the monomers.

Conditions favorable for obtaining high yields of unsaturated hydrocarbons and aromatics in cracking volatile petroleum cracking stocks, such as naphtha cuts, kerosene, or gas oils, are high temperatures of the order of 1000° F. to 1600° F., preferably 1200° to 1500° F., and low pressures of the order of 1 to 10 atmospheres. The charging stock is preferably diluted with up to 90 mole per cent of steam in the cracking zone in order to restrict carbonization.

The hot cracked products issuing from the cracking zone are quenched to a temperature at which hydrocarbons boiling above the naphtha boiling range are condensed, then the naphtha and lower boiling hydrocarbons are fractionated. By processing the highly cracked products formed in this manner, the cycloalkadienes show up in the final naphtha product both as monomers and polymers. It is found that the amounts of the cycloalkadiene monomers present in the low boiling cracked products are so small as to make their separation therefrom unsatisfactory. It is found, however, that the cycloalkadiene polymers can be efficiently collected in a heavy aromatic naphtha fraction of the cracked products without substantial loss by decomposition and that high purity cycloalkadiene monomer cuts can be obtained from the polymers in the heavy aromatic naphtha fraction by a subsequent heat treatment.

In processing the quenched cracked petroleum products, the aromatic naphtha together with the lower boiling hydrocarbons and steam are removed overhead from the higher boiling

cracked products which are quenched to a liquid state. The overhead naphtha vapors and steam are condensed by cooling, but some or all of the normally gaseous hydrocarbons may be allowed to remain in gaseous state. Water condensate is separated from the thus-obtained aromatic naphtha distillate.

After separation of the water condensate, the aromatic naphtha distillate is subjected to a fractional distillation to remove therefrom any remaining condensed C_1 to C_5 hydrocarbons, and if desired, C_6 to C_8 hydrocarbons. This fractional distillation is performed without heating the distillate to above the normal boiling points of C_8 non-aromatic hydrocarbons and may be carried out by passing the distillate into one or a series of topping towers, such as demethanizing, de-ethanizing, depropanizing, debutanizing, and de-pentanizing towers, for removal of the lower boiling C_1 to C_5 hydrocarbons. It is desirable to remove non-aromatic C_6 to C_8 hydrocarbons from the aromatic naphtha distillate if higher cycloalkadiene homologs of cyclopentadiene are to be recovered. It is not necessary to remove the C_6 to C_8 aromatics, but those which distill off with the C_6 to C_8 non-aromatics can be removed therewith, and in removing the C_6 to C_8 hydrocarbons, both aromatic and non-aromatic, it is best to use a distillation aid such as steam or vacuum.

The conditions of the fractional distillation treatment are thus controlled so that the ratio of cycloalkadiene polymers retained in the aromatic naphtha bottoms is kept high with respect to their monomers originally present in the cracked product streams. The remaining aromatic naphtha bottoms following separation of C_5 and lower boiling hydrocarbons boil mainly in the range of 176° F. to 450° F. and following separation of C_6 and C_8 hydrocarbons, the aromatic naphtha bottoms are higher boiling and contain largely alkyl aromatic homologs of benzene with cycloalkadiene polymers.

Following the separation of the C_5 to C_8 and lower boiling hydrocarbons from the aromatic naphtha fraction, the resulting heavier aromatic naphtha bottoms is subjected to a heat treatment in which the temperatures employed are in the range of 300°-800° F. The heat-treated aromatic naphtha bottoms are entirely or partly in vapor phase or entirely in liquid phase depending on the actual temperature and pressure of the heat treatment and the end boiling point of the naphtha.

In general, the end boiling point of the heat-treated naphtha bottoms is not above 500° F. and the heat treatment pressure is atmospheric pressure or slightly thereabove, so that a partial or complete vapor phase operation is obtained. The naphtha bottoms are exposed to the heat treatment for as short a period as is necessary for conversion of the cycloalkadiene polymers to the monomers with minimum cracking or decomposition of other naphtha components to substances which would interfere with separation of the monomers by distillation.

The best results in the vapor phase heat treatment were obtained at temperatures of 600° F. to 800° F. for a duration of 0.15 to 25 seconds. Liquid phase heat treatments require up to 10 hours at 300° F.

The cyclopentadiene monomer liberated by the heat treatment of the aromatic naphtha bottoms is taken overhead by distillation from the cooled or quenched heat-treated naphtha bottoms as a C_5 distillate cut. The heat treatment is thus

controlled to evolve very little of other lower boiling hydrocarbons which would interfere with separation of a high purity cyclopentadiene cut. Any gaseous hydrocarbons formed are readily separated from the quenched heat treated naphtha before liberation of the cyclopentadiene monomer or are separated from the cyclopentadiene monomer distillate taken overhead while repolymerization of the monomer is minimized.

- 10 In a manner similar to that described for obtaining the cyclopentadiene monomer, its homologs, such as, methylcyclopentadiene, dimethylcyclopentadiene and cyclohexadiene can also be separated from the cracked petroleum products,
- 15 with the modification that the aromatic naphtha distillate is freed of C_6 to C_8 hydrocarbons as well as the C_1 to C_5 hydrocarbons prior to the heat treatment. The methylcyclopentadiene and cyclohexadiene polymers along with cyclopentadiene polymers are collected in the heavy ends of the aromatic naphtha distillate and their monomers are liberated by the heat treatment. The monomers can be collected as one or more distillate cuts after which they can be subjected to further distillation, if necessary.

Having outlined the process of the invention in a general manner, further specific details will be explained with reference to the accompanying drawing which schematically illustrates a flow diagram of means and steps in carrying out a preferred embodiment of the invention.

- 30 In the flow diagram 1 represents a high temperature steam cracking zone into which a petroleum cracking stock is charged from line 2 and steam or preheated water is supplied from line 3, the oil charging stock being in the liquid or preheated vapor condition. The cracking zone may be contained in a fired pipe coil or other conventional type of cracking apparatus.
- 35 Steam or preheated water may be supplied at a multiplicity of points to the coil. The cracked products leave the cracking zone through line 4 and are promptly quenched by introduction of cool liquid cycle oil introduced by line 5 into line 4. The quenched cracked products are discharged from line 4 into a fractionation zone 6 from which cracking tars are withdrawn by line 7 and liquid cycle oil is withdrawn as a side-stream by line 8. Cooled cracked naphtha vapors together with steam and gases are drawn overhead from the fractionation zone 6 through line 9 and through cooling condenser 10 into a separation zone 11. Uncondensed gases leave the separation zone through line 12. Water condensate is removed from the bottom of the separation zone through line 13 and naphtha distillate, which may include varying amounts of condensed C_1 to C_5 hydrocarbons, is withdrawn through line 14 from the separation zone 11 to a fractional distillation means 15.
- 40 The uncondensed gases withdrawn from the separation zone 11 through line 12 may be subjected to compression and cooling for liquefaction by means not shown in the drawing and then be combined with the aromatic distillate supplied to the fractionating means 15 for common fractionation therein.
- 45 The fractional distillation means 15 may comprise one or a series of towers, only one being shown for convenience and simplification. In
- 50 the fractionating means 15 the naphtha distillate is kept at as low a temperature as possible during removal of C_1 to C_5 hydrocarbons to minimize decomposition of cyclodiolefin polymers.
- 55 Steam or similar gases may be introduced into

- 70 the fractionating means 15 to assist in the separation of the monomers from the polymers.

the fractionating means for lowering the distillation temperatures of the hydrocarbons which are to be stripped from the aromatic distillate. One or more of the C₁ to C₈ cuts may be jointly or separately removed through the lines 16, 17, 18, 19 and 20 and similarly in certain cases C₈ to C₈ cuts.

In recovering a C₄ cut from the fractionating means 15 as a separate stream withdrawn, for example, through line 19, this stream will contain large amounts of butenes and butadienes mixed with some C₄ paraffins. A C₅ stream withdrawn, for example, through line 20 contains pentenes, pentadienes, C₅ paraffins, and a small amount of cyclopentadiene monomer. The thus-topped aromatic naphtha distillate is withdrawn as bottoms from the fractionating means 15 through line 22 to the heat treating zone 23 which is combined with a fractionating means 24.

As previously mentioned, it is not necessary to remove C₈ hydrocarbons completely, if only cyclopentadiene is to be obtained from its polymers in the aromatic naphtha bottoms and therefore benzene may remain in the bottoms. If C₆ to C₈ cycloalkadienes are to be obtained from their polymers in the aromatic naphtha bottoms, then it is desirable to remove from these bottoms C₆ to C₈ hydrocarbons as well as the C₅ and lighter hydrocarbons and more particularly to remove the C₆ to C₈ non-aromatics.

The heat treating zone 23 may be in the form of a heated tube or tank. In this heat treating zone the topped aromatic naphtha fraction is heated to a temperature in the range of 300°-800° F. and at these temperatures the polymers of cyclopentadiene and its homologs undergo rapid depolymerization to the monomers. The heat-treated aromatic naphtha bottoms is discharged from the heat treating zone 23 through line 25 into the fractionating zone 24 preferably with addition of quenching liquid from line 26. This quenching liquid may be cold water, cold aromatic naphtha distillate bottoms or similar liquid which will not introduce interfering distillation components.

By quenching, the hot products leaving the heat treating zone are suddenly cooled to below 300° F. They may be thus cooled to below 100° F. to avoid cycloalkadiene repolymerization.

Distillation of the heat treatment product following the cooling is carried out in such a way as to minimize polymerization of cycloalkadiene monomers. The distillation preferably follows the quenching immediately. Steam may be introduced into the distillation and fractionation means either directly or as quench fluid. Hold up time in the distillation and fractionation is minimized. The temperature of overhead vapors from the fractionation means 24 should preferably not exceed 120° F.

Overhead of cyclopentadiene vapors are withdrawn from fractionating means 24 through line 27 and cooler 28 into receiver 29 for collection of cyclopentadiene monomer cut. A methylcyclopentadiene fraction may be withdrawn from fractionating means 24 through line 30. Higher boiling homologs may be withdrawn as separate streams from fractionator 24. The remaining high boiling aromatic naphtha freed of polymers of cyclopentadiene and its homologs is withdrawn from the fractionating zone 24 through line 31.

Experimental data were obtained in investigating operations performed in the manner described and tabulated results given in the following table show the distribution of cyclopenta-

diene present as monomer, polymer, or both, in the C₁ to C₈ cuts fractionally distilled from an aromatic cracked naphtha obtained in steam cracking a gas oil at 1250°-1265° F. and remaining in the aromatic naphtha bottoms.

TABLE 1

Distribution of cyclopentadiene in cuts fractionated from a cracked aromatic naphtha distillate

Cut	Cumulative Volume Per Cent Distilled	Final Temp., °F.		Cyclopentadiene, Weight Per Cent in Fraction
		In Still	At Still Head	
15				
1	25	154	97	0.0
2	50	205	-----	0.5
3	75	284	190	0.1
4	80	318	185	3.9
5	85	349	208	3.9
6	90	395	194	4.7
7	95	547	248	4.4

The cyclopentadiene present in the cuts 1, 2 and 3 represented the original cyclopentadiene monomer which has a normal boiling point of 105.8° F. The results show that a preponderance of the cyclopentadiene in the cracked aromatic naphtha distillate was present as polymer.

Typical data obtained in the heat treatment of the topped aromatic naphtha are shown in the following tables:

TABLE 2

Yields of cyclopentadiene from its dimer in topped aromatic naphtha distillates of steam cracked oils

Heat Treatment Temp., °F.	Contact Time, Seconds	Wt. Per Cent Liquid Recovery	Wt. Per Cent Cyclopentadiene Yield Based on Naphtha Before Topping	Wt. Per Cent Cyclopentadiene Loss in Topping
			2.2	0.02
690	21	90	2.2	0.02
700	18.9	95	2.8	0.04
700	0.2	100	3.1	0.0

TABLE 3

Yield of cyclopentadiene from a synthetic mixture of 4.56 wt. per cent dicyclopentadiene in aromatic naphtha of 300-400° F. boiling range

Heat Treatment Temp., °F.	Contact Time, Seconds	Wt. Per Cent Liquid Recovery	Wt. Per Cent Yield of Cyclopentadiene
715	21.3	98	4.1

TABLE 4

Recovery of cyclopentadiene and alkyl homologs of cyclopentadiene by depolymerization of dimers in cracked distillate topped to remove C₅ and lower boiling components

Reactor Temp., °F.	Contact Time, Sec.	Per Cent Liquid Recovery	Wt. Per Cent Yield From Aromatic Distillate	
			Cyclopentadiene	Substituted Cyclopentadiene
500	22.9	96	2.0	0.25
700	17.8	93	2.7	0.24

The points of interest shown by the data in the Tables 2, 3 and 4 are summarized as follows:

(a) Cyclopentadiene losses resulting from the

topping of the aromatic naphtha distillate as carried out are small (Table 2);

(b) Recovery of monomer from the heat treated dilute solution of polymer in aromatic naphtha fraction is good, of the order of 90% or better (Table 3);

(c) A higher yield of cyclopentadiene is obtained with heat treatments of shorter duration at 600°-800° F. than at 300°-600° F. (Table 4);

(d) In obtaining the results shown in Table 4, the C₅ fraction distilled overhead from the heat treated aromatic naphtha bottoms was substantially 100% cyclopentadiene and the C₆ fraction obtained was substantially 100% methylcyclopentadiene. Other hydrocarbons were hardly detectable in these two distillate fractions.

(e) High purity and yields of cycloalkadiene products are obtained by the method of topping, heat treating the topped naphtha (bottoms) under proper conditions, and fractionating these products from the heat treated naphtha bottoms (Tables 2, 3 and 4).

The separation of the cycloalkadienes in the manner described is helpful to the recovery of the non-cyclic diolefins and advantageously improves the stability of the final aromatic naphtha product.

The cycloalkadienes recovered in the manner described are useful in chemical reactions as monomers or they may be subsequently converted to pure dimers or high polymers by thermal or catalytic polymerization methods. These materials are important in the manufacture of highly unsaturated oils, plastic polymers and resins which may be utilized in surface coatings, ink oils, various drying compositions, synthetic fibers, etc. The invention has been described with reference to preferred modifications and adaptations, but it is to be understood that other modifications come within the scope of the invention as defined in the appended claim.

We claim:

A process of producing and recovering monomeric cyclopentadiene of high purity in cracking a petroleum oil boiling in the heavy naphtha and gas oil range, which comprises cracking the petroleum oil in vapor phase at a temperature in the range of 1000° F. to 1600° F. in the presence of steam under a pressure of 1 to 10 atmospheres, promptly quenching the resulting cracked petroleum products to a temperature at which thermal polymerization of unsaturated hydrocarbons is

repressed, separating from the quenched cracked products an aromatic naphtha distillate fraction containing cyclopentadiene monomer and cyclopentadiene dimer distilled with steam, distilling C₁ through C₅ hydrocarbons including the cyclopentadiene monomer from said aromatic naphtha distillate fraction to obtain a residual fraction of the aromatic naphtha boiling in the range of 176° F. to 450° F. and containing the cyclopentadiene dimer in low concentration with higher boiling aromatic hydrocarbons, continuously passing said aromatic fraction in liquid phase, without intermediate separation of the cyclopentadiene dimer as vapor therefrom, through a depolymerization reaction zone at a temperature of 300° F. to 600° F. to decompose the cyclopentadiene dimer contained in the liquid phase aromatic hydrocarbons, continuously withdrawing from said reaction zone an effluent of the liquid aromatic hydrocarbons from the heat treated aromatic fraction and the cyclopentadiene monomer vapor formed by depolymerization of the dimer, immediately cooling the withdrawn cyclopentadiene monomer vapor and fractionating said vapor in a fractional distillation zone in which the overhead vapors have a temperature not exceeding 120° F. to obtain an overhead distillate of cyclopentadiene monomer substantially free of other hydrocarbons.
